Primary Examiner—Jeffrey Asch

[57] CLAIM

The ornamental design for the child's telephone, as shown and described.

DESCRIPTION

FIG. 1 is a front elevational view of the child's telephone showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showings of FIG. 1 are for illustrative purposes only and form no part of the claimed design.
